UNITED STATES PATENT OFFICE.

CHARLES F. COLEMAN, OF PHILADELPHIA, PENNSYLVANIA, ASSIGNOR TO F. J. STOKES MACHINE COMPANY, OF PHILADELPHIA, PENNSYLVANIA, A CORPORATION OF PENNSYLVANIA.

METHOD OF IMPREGNATING WITH A COMPOUND.

Application filed May 26, 1925. Serial No. 32,909.

The present invention has to do mainly with improving the dielectric qualities of high tension electrical cables after they have been wrapped with paper or equivalent binder or wrapper, by saturating them with a dielectric compound in a melted or liquid state. The compound usually includes vaseline and resin. However, the invention is applicable in whole or in part to saturating or impregnating other material with the same or with other substances.

The principal objects of the present invention are, first, to materially and substantially reduce the time consumed in the process; and second, to improve the dielectric property or quality of the cable by permitting the compound to set or solidify under such pressure as will prevent the occurrence of voids due to shrinkage.

20 The invention will be claimed at the end hereof but, generally stated, it may be said to comprise the method of impregnating material with a melted or heat softened compound which consists in removing the moisture and air from the material to be impregnated by subjecting it to heat and vacuum in a closed chamber, impregnating the dried and air freed material by subjecting it in the chamber to the action of the melted or heat softened impregnating compound under pressure, and cooling the impregnated material by subjecting the impregnating compound, to circulation and heat exchange with or without agitation.

35 The invention also comprises the improvements to be presently described and finally claimed.

In the following description reference will be made to the accompanying drawing forming part hereof and in which

40 Figure 1 is a top or plan view, and

Fig. 2 is an elevational view with parts broken away.

In the drawing 1 and 2 are vessels or 45 chambers to which heat is applied as by jackets 3, and they are adapted to be closed.

The chamber 1 is a tank in which the impregnating compound is prepared, mixed and melted. The chamber 2 is adapted to 50 receive the material to be impregnated, for example, high tension electrical cable wound on drums adapted to be accommodated by the vessel or chamber 2. 4 is a vacuum connection for the chamber 2. 5 is a cooler

illustrated as a heat exchanger shown as 55 having a jacket 6 for cooling fluid such as water. The heat exchanger 5 is shown as also provided with an agitator 7 that can be driven from the pulley 8 and is in the nature of a scraper for the inner wall of the 60 heat exchanger or cooler 5. There is a pressure connection 9 which extends between and communicates with vessels or chambers 1 and 2, and this connection 9 may include strainers 10, and it is provided with a pump 65 11 around which extends a by-pass connection 12 having a relief valve 13. There is a connection 14 from the bottom of the chamber or vessel 2 to the bottom of the cooler or heat exchanger 5, and from the top of the 70 latter to the top of the vessel or chamber 2. This connection 14 includes a pump 15, and a valve 16, and it may be fitted with a strainer 17.

In the practice of the invention the material to be impregnated, for example high tension electrical cable wound upon a drum, is subjected to heat and vacuum in the closed chamber 2. For this purpose use may be made of the vacuum connection 4, and the 75 purpose is to remove moisture and occluded air from the material so that when the impregnating or saturating compound is introduced it can enter the material without air resistance. The vacuum connection may be 80 closed and the dried and air free material in the vessel or chamber 2 is subjected to the action of melted or heat liquefied impregnating compound under liquid pressure. For this purpose the mixed and melted 85 impregnating material in the tank or vessel 1 is pumped by the pump 11 into the vessel or chamber 2, where it submerges the material to be impregnated and where a pressure of, without limitation, 80 to 100 pounds 90 will be built up. The liquid pressure thus applied may be regulated by adjustment of the relief valve 13 which operates to provide limited flow from the pressure to the suction side of the pump. The liquid pressure 95 operates to accelerate the rate of impregnation and it has the advantage that moisture is not introduced as would be done if pressure were obtained by compressed air. Upon completion of the impregnating step the impregnated material is cooled in a comparatively short time by circulating the impregnating compound while still un-

der pressure through the cooler or heat exchanger 5 where it gives up its heat to the cooling fluid and where it is prevented from accumulating on the heat exchange wall by 5 the agitation or scraping action of the element 7. Inasmuch as the heat exchange surface is kept free from accumulations of solidified compound, the heat exchange is facilitated and the time required for cooling 10 is shortened. Impregnating compound at the end of the operation may be returned to the mixing tank 1 by reversing the direction of operation of the pump 11. Of course the heat may be turned off from the vessel 15 2 during the cooling operation.

There is an advantage in cooling the impregnating compound while under pressure greater than atmospheric although many persons may not elect to employ it, and that 20 advantage may be described as follows: By the vacuum, immersion and pressure step the wrappings of paper or other substance of the cable are impregnated, and as the impregnating compound solidifies by cooling 25 it tends to shrink and produce voids such as might and probably would impair the quality of the cable. However, by keeping the impregnating compound under pressure as it solidifies, as in my invention, the 30 formation of objectionable voids is obviated and the impregnation is complete throughout, because any loss due to shrinkage is offset or made up by fresh compound supplied under pressure.

35 It will be obvious to those skilled in the art to which the invention relates that mod-

ifications may be made in details of construction and procedure and in mere matters of form without departing from the spirit of the invention which is not limited 40 as to such matters or otherwise than the prior art and the appended claims may require.

I claim:

1. In the method of impregnating material by subjecting the material in a closed vessel to vacuum action and to an impregnating compound rendered fluid by heat, the improvement which consists in applying mechanical pressure to the fluid compound 50 and thus opposing the introduction of moisture, cooling the material by circulating the compound under mechanically applied pressure into and out of the vessel in a path external to the vessel, and cooling 55 the circulating compound in said external path by heat exchange.

2. In the method of impregnating material by subjecting the material in a closed vessel to vacuum action and to an impregnating compound rendered fluid by heat, the improvement which consists in applying mechanical pressure to the fluid compound and thus opposing the introduction of moisture, cooling the material by circulating the compound under mechanically applied pressure into and out of the vessel in a path external to the vessel, and cooling the circulating compound in said external path by heat exchange and agitation.

CHARLES F. COLEMAN.
